[57] **CLAIM**

The ornamental design for a desktop computer system support device with integrated cable management, as shown and described.

DESCRIPTION

FIG. 1 is a front left perspective view of a desktop computer system support device with integrated cable management showing our new design;

FIG. 2 is a bottom left perspective view thereof;

FIG. 3 is a bottom plan view thereof, on an enlarged scale;

FIG. 4 is a top plan view thereof, on an enlarged scale;

FIG. 5 is a front elevational view thereof;

FIG. 6 is a front right perspective view thereof;

FIG. 7 is a rear left perspective view thereof; and,

FIG. 8 is a rear right perspective view thereof.

FIG. 1

FIG. 2

FIG. 3

FIG. 4

FIG. 5

FIG. 6

FIG. 7

FIG. 8
